Patented Mar. 22, 1921.

Inventor

W. Tankersley

By Watson E. Coleman

Attorney

UNITED STATES PATENT OFFICE.

WILLIAM TANKERSLEY, OF DENVER, COLORADO, ASSIGNOR OF ONE-TENTH TO
EARL B. SMITH, OF COLORADO SPRINGS, COLORADO.

WRENCH.

1,372,662.

Specification for Design.

Patented Mar. 22, 1921.

Application filed August 2, 1920. Serial No. 400,771.

To all whom it may concern:

Be it known that I, WILLIAM TANKERSLEY, a citizen of the United States, residing at Denver, in the county of Denver and State 5 of Colorado, have invented certain new and useful Improvements in Wrenches of which the following is a specification, reference being had to the accompanying drawings.

This invention relates to certain improvements 10 in wrenches, and it is primarily an object of the invention to provide a novel and improved device of this general character which is an improvement over the type of wrench disclosed in my prior Patent No. 15 1,293,243, dated February 4, 1919.

It is also an object of the invention to provide a novel and improved device of this 20 general character including a shank consisting of a plurality of sections connected for relative angular adjustment, together with 25 means for positively locking said sections in their various arrangements.

The invention consists in the details of 30 construction and in the combination and arrangement of the several parts of my improved wrench whereby certain important advantages are attained and the device rendered simpler, less expensive and otherwise, more convenient and advantageous for use, 35 as will be hereinafter more fully set forth.

The novel features of my invention will 40 hereinafter be definitely claimed.

In order that my invention may be the 45 better understood, I will now proceed to 50 describe the same with reference to the accompanying drawings, wherein:

Figure 1 is a side elevation of my improved wrench,

Fig. 2 is a longitudinal sectional view of 40 a portion thereof, and

Fig. 3 is an edge or plan view of the device.

As disclosed in the accompanying drawings, 45 S denotes the shank of my improved wrench which consists of two sections 1 and 2. The inner end of the section 1 is provided with a pair of transversely spaced wings or leaves 3 which extend beyond a face of the section 1 and which are substantially 50 circular in contour and of equal radii.

Snugly fitting between the wings or leaves 3 is a substantially circular head 4 carried by the inner end of the section 2 and disposed through the axial center of the wings 55 or leaves 3 and the head 4 is the pin 5 whereby the sections 1 and 2 are pivotally con-

nected so that said sections may be angularly adjusted one relative to the other. The periphery of the head 4 terminates a material distance inwardly of the periphery of the wings or leaves 3 so that in practice the peripheral portion of the head 4 will be protected and more particularly the outer or entrance ends of the recesses 6 produced in the periphery of said head.

The inner end of the section 2 at opposite sides of the head 4 is provided with the inwardly directed ribs 7 which overlie the marginal portions of the wings or leaves 3, whereby said wings or leaves are materially reinforced during a working operation.

The section 1 at substantially its axial center is provided with a longitudinally disposed bore or opening 8 open at the inner end of the section 1. Extending within 75 said bore 8 and having sliding movement longitudinally thereof is a cylindrical shank 9 having its inner or inserted end continued by a reduced extension 10. The extension 10 and the coacting annular shoulder 11 at 80 the inner end of said extension provide a seat for the spiral spring 12, the opposite end of said spring bearing against the inner or closed end of the bore 8 whereby the shank 9 is constantly urged outwardly.

The outer end of the shank 9 is provided with a laterally extending lug 14 terminating in a forwardly directed tongue 15, said tongue 15 being adapted to engage within a recess 6 so that the sections 1 and 2 90 may be effectively locked in alinement or at different relative angles as occasioned by the requirements of practice and as permitted by the recesses 6. As is clearly illustrated in Fig. 2 of the accompanying drawings, the lug 14 is of a length whereby the tongue 15 is positioned radially of the connecting pin 5.

A face of the section 1, or the outer face thereof when the sections 1 and 2 are in 100 folded relation, is provided with a longitudinally directed slot 16 in communication with the bore 8. Disposed through the slot 16 is a shank 17 in threaded engagement or otherwise secured to the shank 9 and at such 105 a point on said shank 9 whereby the contact of the shank 17 with the inner end of the slot 16 limits the inward movement of the shank 9 with the outer face of the lug 14 substantially flush with the inner end of the 110 section 1 and at which time the tongue 15 seats within a recess 6. The slot 16 is of a

length to permit the requisite endwise movement of the shank 9 to withdraw the tongue 15 from within a recess 6 when the shank 17 is at the limit of its outward movement 5 and as controlled by the outer end of the slot 16.

The outer end of the shank 17 is integrally connected with a head 18 herein disclosed as hexagonal in form and having its outer 10 face serrated or otherwise roughened so that the same may effectively serve as an operating medium for imparting the desired movement to the shank 9 in an outward direction along the section 1, it being understood 15 that the head 18 is adapted to be engaged by a digit of a hand.

The outer end of the section 1 is provided with a pair of laterally directed jaws *a* and *b*, one movable relative to the other, and 20 which project beyond the section 1 in the same general direction as the wings or leaves 3. The desired relative movement of the jaws *a* and *b* is obtained in the same manner as set forth in my prior Patent No. 25 1,293,243, hereinbefore referred to.

The outer end of the section 2 is also of a construction and form as is particularly illustrated in my prior patent just referred to and which includes the relatively movable 30 jaws *c* and *d* and an opening 19 with which is adapted to be engaged a suitable handle or lever for imparting the requisite turning or swinging movement to the shank *S* when the occasions of practice may so require.

35 From the foregoing description it is thought to be obvious that a wrench constructed in accordance with my invention is particularly well adapted for use by reason of the convenience and facility with

which it may be assembled and operated, 40 and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

A wrench comprising, in combination, a shank consisting of two sections, a hinge joint therebetween to fold the sections one upon the other or at intermediate angles, one of the hinge joint members having a 55 series of recesses, the adjacent end portion of the second section being provided with a longitudinally disposed bore, a shank slidably mounted in said bore, means for constantly urging said shank toward the hinge joint, the outer end of the shank being provided with a laterally extending lug terminating in a forwardly directed tongue adapted to engage within a recess carried by one of the hinge joint members, said 65 tongue being disposed radially of the hinge joint, said second section of the shank being provided with a longitudinally disposed slot in communication with a bore therein, a shank disposed through said slot and secured to the shank, said second named shank constituting an operating member, and a 70 head carried by the outer end of said second named shank and adapted to be engaged by the digit of a hand.

In testimony whereof I hereunto affix my signature.

WILLIAM TANKERSLEY.
